E. Naldrett

UNITED STATES PATENT OFFICE.

EDGAR NALDRETT, OF EDMONTON, ALBERTA, CANADA.

RAIL ANCHOR.

Application filed March 27, 1925. Serial No. 18,909.

To all whom it may concern:

Be it known that I, EDGAR NALDRETT, a subject of the King of Great Britain, and resident of the city of Edmonton, in the 5 Province of Alberta, Canada, have invented certain new and useful Improvements in Rail Anchors, of which the following is the specification.

The invention relates to improvements in rail anchors and an object of the invention is to provide an anchor which will prevent creeping of the rail under the action of traffic and which also allows of a floating 10 vertical movement of the rail due to bending under traffic and by so doing prevents the fastening spikes from being heaved loose and the tie from being pounded up and down in the road bed.

A further object of the invention is to 20 provide a rail anchor of comparatively few parts and which can be readily manufactured and which can be readily placed in position on the tie and rail.

A further object is to construct the anchor 25 so that any upsetting action of the rail is prevented whilst permitting of the vertical floating movement above intimated.

With the above more important objects in view, the invention consists essentially in 30 the arrangement and construction of parts hereinafter more particularly described, reference being had to the accompanying drawings, in which:

Fig. 1 is a side view of the anchor applied 35 on the rail and secured to the tie, the rail being shown in vertical section.

Fig. 2 is a plan view of the parts appearing in Figure 1.

Fig. 3 is a vertical sectional view at 3—3'

Fig. 1.

Fig. 4 is a perspective view of the tie plate.

Fig. 5 is a perspective view of the anchor block.

Fig. 6 is an enlarged detailed perspective view of the wedge.

In the drawing like characters of reference indicate corresponding parts in the several figures.

The track rail is of the customary type presenting a head 1, web 2 and base 3. The

anchor which I provide embodies an anchor plate 4, similar pairs of anchor blocks 5 and 6 and four similar wedges 7.

The tie plate is substantially rectangular and is placed beneath the rail and sits on the customary tie 8. The body or that part of the tie plate lying underneath the rail is substantially horizontal and is normally elevated above the tie, being held in such position by having the ends 9 and 10 of the plate inclining outwardly and downwardly at a slight angle as best shown in Figure 1. The ends of the tie plate are fitted with spike holes 11 and 12 and the plate is fastened to the tie by spikes 13 and 14 driven through the spike holes. By making the tie plate arched in this manner, there is a natural tendency under the weight of traffic for the ends of the tie plate to embed themselves in the tie.

The opposite sides of the tie plate are provided with upstanding pairs of opposing similar lugs forming abutments or guides 15, 16, 17 and 18 and these abutments are located outwardly a short distance from the rail base and have their inner faces 19 inclining upwardly and outwardly at a slight angle as shown. In the present instance, these abutments or lugs are formed from the material of the tie plate being cut therefrom and bent upwardly. The pairs of anchor blocks 5 and 6 are more or less of a U-shape and each presents upper and lower jaws 20 and 21 connected by an intervening neck 22. The jaws are adapted to span the edges of the rail base and the lower jaws when in place enter the openings or slots indicated at 23 formed in the tie plate. There are two pairs of wedges 7 and these wedges are gradually tapered and present a large and small end, both the width and thickness of the small end being less than the width and length of the large end.

When the device is to be used, the tie plate is slipped under the rail from the side of the tie and is spiked in place centrally in respect to the rail. The anchor blocks are then put in place by moving them laterally into position and without raising the rail. The small ends of the wedges are then entered between the jaws 20 and the rail base

and are driven home by a sledge. The large ends of the wedges are all outermost. After the wedges have been driven home, the inner or thin ends thereof are bent upwardly 5 into a position such as shown in dotted outline in Figure 3 which prevents them from withdrawing.

A rail carried by rail anchors of the type shown is prevented from creeping as the 10 wedges hold the rail base to the anchor blocks and the inner sides of the anchor blocks butt against the edges of the tie plate. The rail is also permitted to move or float vertically during bending under 15 traffic as it will be obvious that the anchor blocks can move upwardly in relation to the abutments and whilst being maintained tightly fastened to the rail base by the wedges. The slight inclination given the 20 inner faces of the abutments is designed to give a slight clearance which permits the rail and anchor blocks secured thereto to rise and fall under the action of traffic. This floating feature prevents the spikes 25 from being loosened and avoids any pounding of the tie by the rail. The friction surface between the anchor blocks and the abutments is sufficient to prevent any overturning of the rail under all conditions. 30 If it should be desired to lock the rail against the floating action above described, it is only necessary to have the inner faces 19 of the guides 15, 16, 17 and 18 inclining upwardly and inwardly in which case the 35 guides would positively prevent any up movement of the anchor blocks.

Whilst I have particularly described the floating feature of the rail, it might be considered however by railroad experts that 40 such is undesirable and accordingly I have latterly mentioned the manner in which this floating can be avoided if desired. The article is none the less a novel type of rail anchor regardless of whether the faces 45 are vertical or are pitched slightly upwardly and inwardly.

What is I claim as my invention is:—

1. The combination with a track rail and tie, of a tie plate underlying the rail and secured to the tie and provided with up- 50 standing guides and members anchored to the edges of the rail base and slidably engag- 55 ing the guides, said guides and members permitting of a movement of the rail in a vertical direction and preventing any lateral displacement thereof during such movement.

2. The combination with a track rail and tie, of a tie plate underlying the rail and secured to the tie and provided with up- 60 standing guides and members anchored to the edges of the rail base and slidably engag- 65 ing the guides and in contact with the edges of the plates, said guides and members permitting of a movement of the rail in a

vertical direction and preventing any lateral displacement thereof during such movement and further preventing any creeping of the rail.

3. The combination with a track rail and tie, of a tie plate underlying the rail and secured to the tie and provided with opposing upstanding guides spaced from the edges of the rail base and intervening members clamped to the opposite edges of the rail 75 base and slidably engaging the guides and abutting the edges of the tie plate.

4. The combination with a track rail and tie, of a tie plate underlying the rail base and provided with upstanding guides spaced 80 from the edges of the rail base and having slots provided in the edges thereof adjacent the inner sides of the guides, members clamped to the edges of the rail base and ex- 85 tending into the slots and in sliding engage- 90 ment with the guides.

5. The combination with a track rail and tie, of a tie plate underlying the rail base and spiked to the tie and provided with up- 95 standing guides spaced from the edges of 90 the rail base and having slots formed in the edges thereof within the guides, anchor blocks gripping the edges of the rail base 95 slidably engaging the guides and extending into the slots.

6. The combination with a track rail and tie, of a tie plate underlying the rail base and spiked to the tie and provided with op- 100 posing upstanding guides spaced from the edges of the rail base and having slots in the 100 edges thereof underlying the rail base and within the guides, pairs of similar anchor blocks anchored to the edges of the rail base and making sliding contact with the guides and having the lower ends thereof underlying 105 the rail entering the slots and contacting with the inner sides of the slots.

7. The combination with a track rail and tie, of an anchor plate underlying the rail base and spiked to the tie and provided 110 with pairs of opposing upstanding guides spaced from the edges of the rail base and having slots appearing in the edges of the plate within the guides, similar anchor blocks spanning the edges of the rail base 115 and presenting upper and lower jaws and making sliding contact with the guides and having the lower jaws thereof entering the slots and abutting the inner sides thereof and wedges driven in between the upper jaws 120 and the rail base.

8. In a device of the class described, a rail tie plate having opposing upstanding guides spaced apart a distance greater than the width of the rail base and having slots 125 formed in the edges thereof, the slots ex- 130 tends inwardly from the bases of the up- standing guides.

9. In a device of the class described, an arched tie plate having opposing pairs of 130

upstanding guides spaced apart a distance greater than the width of the rail and slots formed in the edges of the plate at the bases of and within the guides.

5 10. The combination with a track rail and tie, of a tie plate underlying the rail base and provided with upstanding lugs spaced from the edges of the rail base and having

slots provided in the edges thereof to the inner sides of the lugs, members clamped ¹⁰ to the edges of the rail base and extending into the slots and in contact with the lugs.

Signed at Edmonton, Alberta, this 6 day of February, 1925.

EDGAR NALDRETT.
